UNITED STATES PATENT OFFICE.

EFFIE SEACHREST, OF KANSAS CITY, MISSOURI.

DESK ATTACHMENT.

No. 839,654.

Specification of Letters Patent.

Patented Dec. 25, 1906.

Application filed January 2, 1906. Serial No. 294,324.

To all whom it may concern:

Be it known that I, EFFIE SEACHREST, a citizen of the United States, residing at Kansas City, in the county of Jackson and State 5 of Missouri, have invented certain new and useful Improvements in Desk Attachments, of which the following is a specification, reference being made to the accompanying drawings.

10 My invention relates to attachments for desks, particularly school-desks, by which receptacles for water-color mixtures, paints, inks, and other fluids may be detachably attached to the desk.

15 An object of my invention is to provide a desk attachment by which the cup or receptacle is held away from the desk at all times, thereby preventing the liquid from coming into contact with the varnish upon the desk 20 and thereby marring it.

Another object of my invention is to provide a desk attachment which will permit the cup to be readily removed from one position to another. The liquid in the cup can 25 always be kept ready for use as the cup needs to be moved only from one position to another. The economy in time is obvious.

30 A third object of my invention is to provide a desk attachment which may be readily positioned and which will be securely held in its adjusted position.

35 In the drawings illustrating the principle of my invention and the best mode now known to me of applying that principle, Figure 1 is a perspective view showing the cup in full lines in its position when not in use and in dotted lines in its position when in use. Fig. 2 is a side elevation of the cup, and Fig. 3 is a like view of the clasp-support.

The clasp-support is shown in Figs. 1 and 3 40 and is preferably made of spring-steel or other suitable resilient material. It is S-shaped, and the bow *a* is adapted to arch over the upper edge of the front *b* of the desk *c*, the legs *d* *e* being pressed firmly by spring 45 action against the sides of the portion *b*, thereby securing the clasp-support in place. The upper free end *f* of the clasp-support is formed with two inwardly-projecting ears *g* 50 *g*, adapted to engage the hook *h*, with which the cup *i* is provided. The clasp-support is designed to remain in position upon the front of the desk, and when the cup is no longer needed it is raised so as to disengage its hook *h* from between the ears *g*, and its hook *h* is 55 then engaged with the fretwork *j* of the desk. Thus when the cup is not in use it may be placed at the side of the desk out of the way, its contents ready for instant use, and when the cup is needed it may be placed in position 60 in its clasp-support at the front of the desk in a moment. This arrangement results in economy of time and material. The clasp-support may be readily adjusted in position along the edge of the front portion *b* of the 65 desk.

What I claim is—

The combination, with an S-shaped hook formed of resilient metal, and provided on one end with inwardly-projecting ears, of a 70 cup having a downwardly-projecting hook adapted to engage loosely said ears, as and for the purpose set forth.

EFFIE SEACHREST.
